UNITED STATES PATENT OFFICE.

ARTHUR TREVOR DAWSON, OF LONDON, AND JAMES HORNE, OF BARROW-IN-FURNESS, ENGLAND, ASSIGNORS TO VICKERS SONS & MAXIM, LIMITED, OF LONDON, ENGLAND.

AMMUNITION-HOIST FOR ORDNANCE.

SPECIFICATION forming part of Letters Patent No. 736,075, dated August 11, 1903.

Application filed August 19, 1901. Serial No. 72,629. (No model.)

To all whom it may concern:

Be it known that we, ARTHUR TREVOR DAWSON, late lieutenant of Royal Navy, residing at 32 Victoria street, Westminster, London, and JAMES HORNE, engineer, of Vickers Sons & Maxim, Limited, Naval Construction Works, Barrow-in-Furness, in the county of Lancaster, England, subjects of the King of Great Britain, have invented certain new and useful Improvements in Ammunition-Hoists for Ordnance, of which the following is a specification.

Our invention relates to hoisting apparatus for supplying powder charges and projectiles to the platforms or turn-tables of turret or similar gun mountings and is designed to afford means for raising such charges and projectiles safely and rapidly to the platform, and is particularly advantageous for maintaining a continuous supply to a pair of guns in a turret or barbette mounting. We use chains provided with suitable receptacles for taking up powder charges or projectiles in a horizontal position from a ship's hold or other magazine to the platform. The chains are arranged to pass over sprocket-wheels at the top and bottom of a trunk or frame attached to the turn-table or platform, and there are inclined trays at the bottom of the hoist; suitably formed to receive the charges or projectiles and transfer them to the receptacles on the chains as they move upward. The said receptacles travel around these sprocket-wheels, and in rising with a charge or load each receptacle delivers its charge to an inclined tray at the side of the mounting just below the gun-platform. By arranging this apparatus in duplicate a continuous supply of powder charges or projectiles can be maintained on both sides of the mounting, the charges being delivered in a convenient position for transferring them by hand from the inclined trays to the breach of the gun. The apparatus can be arranged to carry up and deliver the projectiles on one side and the powder charges on the other side of the mounting. In the apparatus above described we arrange the chains to travel upward on the outer side or sides of the sprocket-wheels.

According to our invention we hinge the

receptacles or buckets to the chains, so that in passing the upper inclined tray they will engage with the edge of the same and will be thereby so tilted as to allow the charge or projectile to roll from the buckets into the 55 said tray. A suitable device, such as a spring on the hinge, restores the bucket to its original position after it has passed the tray.

In some cases we employ a single chain and hinge every alternate receptacle or bucket 60 thereto, so that the load carried by the hinged buckets will be delivered on one side of the chain near the top of the hoist and the load carried by the fixed buckets will be delivered on the opposite side.

In order that our said invention may be clearly understood and readily carried into practice, we will proceed to describe the same more fully with reference to the accompanying drawings, in which—

Figure 1 is a vertical section of the upper end of the hoist, showing a single chain provided with alternately hinged and fixed ammunition-receptacles. Fig. 2 is a transverse section, on a larger scale, of one of the hinged 75 receptacles with which the aforesaid chains are provided.

B is the rotary platform or turn-table, upon which the guns are mounted. C is the vertical trunk or frame attached to the said platform or turn-table so as to revolve therewith, and D is the chain hoist by means of which the powder charges and projectiles are conveyed from the bottom of the said trunk or frame to the gun-platform. The said chains 80 D are arranged within the trunk C and at their opposite ends pass around sprocket-wheels d d.

d' d' are the hinged receptacles, and d'' are the fixed receptacles on the aforesaid chains 90 for receiving the powder charges or projectiles from trays located near the bottom of the trunk C. The said hinged receptacles are connected to the chains by means of pivot-pins d'', so that they are capable of turning 95 downwardly and outwardly with respect to the chains. For actuating the said receptacles we provide each of them with a lip d'', which is adapted to pass unchecked through the lower trays, but which will upon reach- 100

ing the upper tray d^4 engage with the edge of the latter. The hinged receptacle will thus be tilted to an extent sufficient to expel the charge or projectile it contains into the said tray d^4 , the said hinged receptacle regaining its normal position by a spring d^{10} , Fig. 2, or otherwise as it is carried along by the chains D over the upper sprocket-wheels. We wish it to be understood that we do not confine ourselves to any specific manner of causing the aforesaid hinged receptacles to be tilted, as any suitable means may be employed for this purpose.

The receptacles d^{*x} are adapted to pass the tray d^4 unchecked and to deliver their contents into the tray d^{4x} as they pass over the upper sprocket-wheels and become inverted.

In order to prevent the charges or projectiles transferred from the chains D to the trays d^4 d^{4x} from rolling back toward the open end of the said trays, we provide spring-flaps d^5 , so arranged that they will give way to permit the charge or projectile to enter the said tray, but will operate as stops to prevent the said charge or projectile from returning. The charges or projectiles having been delivered to the aforesaid trays can be transferred therefrom by hand and conveyed to the breeches of the guns in any suitable manner.

What we desire to claim and secure by Letters Patent of the United States is—

1. In ammunition-hoists for ordnance, the combination with the hoisting-chain, of am-

munition-receptacles alternately hinged and fixed thereto, and a plurality of trays near the top of the hoist, one of said trays being located within the path of movement of, and adapted to be engaged by, the hinged receptacles, but incapable of being engaged by the fixed receptacles, whereby the load carried by said hinged receptacles will be delivered into one tray, and the load carried by the fixed receptacles will be delivered into the other tray.

2. In ammunition-hoists for ordnance the combination with the hoisting-chains and the trays near the top of the trunk for receiving the ammunition, of outwardly-opening spring-flaps pivoted at their upper ends, and having their lower ends projecting down into said trays for preventing the ammunition from returning from said trays after being supplied thereto, substantially as described.

In testimony whereof we have hereunto set our hands, in presence of two subscribing witnesses, this 8th day of August, 1901.

ARTHUR TREVOR DAWSON.
JAMES HORNE.
